Ms. A75

Richard Peterson Assignee of
Stuart Seibert & Peterson of Philadelphia Pa.
Letters Patent No 245.

The Schedule referred to in these Letters Patent and making part of the same.

To whom it may concern:

Be it known that we Richard Peterson, David Stuart and Peter Seibert all of the County of Philadelphia in the State of Pennsylvania, have invented or produced a new and useful design which is intended to ornament a store called a complete

Cook and do hereby declare that the following is a full and exact description of the same.

Fig. 1. Is intended to represent the bottom or hearth plate it is ornamented on the outer edge by a succession of leaves and scrolls as at a, a, a, a, and in front is a ventilator ornamented on the outer edge by a succession of scrolls as at b, b, b, b, and on the inside by a corner scroll repeated 4 times as at c, c, c, c.

Fig. 2. Represents the front plates immediately in front of oven ornamented on the outer edge by a bead as at a, a, a, a, within the lines of the bead work is a succession of scroll work and leaves very beautifully designed as at b, b, b, b, which is crowned with a very beautiful collection of flowers and leaves as at c, c, c.

Fig. 3. Represents the draft door or feeder door which is ornamented by a bead as at c, c, c, c, and within by a succession of flowers and scroll work as at b, b, b.

Fig. 4. Represents the two front doors being ornamented at the top and sides by a scroll and flower work very beautifully designed as at a, a, a, a, at the bottom we have a very pretty scroll as at c, c, c, on the centre we have a chain work as at b, b.

Fig. 5 & 6. Represents the fire and oven door ornamented on the outer edge with a succession of leaf and scroll work as at a, a, a, a, and the centre of each having a very pretty flower work running down to each corner as at c, c, c, c, finished on the bottom with leaf work as at b, b, b, b.

Fig. 7. Represents the back plate with bead work on margin as at c, c, c, c.

We have thus described the ornamental design which we claim as our invention or production and desire to secure by Letters Patent the design for a stove called a Complete Cook herein fully described and represented in the accompanying drawings.
